CIRCULAR WARP LOOM

Eugen Hiller, Berlin, Germany

Application May 10, 1937, Serial No. 141,822
In Germany May 13, 1936

4 Claims. (Cl. 66—81)

This invention relates to a circular warp loom of the type in which, on a circular ring a needle group is obliquely placed, to which as a whole during the straight lined to and fro movement two threads are fed for each needle from warp beams moving in opposite directions and with the aid of thread feed rings or thread guides also moving in opposite directions, said threads being gripped at their point of intersection by the individual needle. In a circular knitting frame of this type the one group of threads moves in clockwise direction and the other group moves in anticlockwise direction, and at each up and down movement of the needle ring as many loops are produced as needles are provided. The object of this invention is to produce a circular knitting frame of this type, by means of which it is possible to produce ribbed tubular goods.

This object is substantially attained by providing an inner and outer needle plate lying at an acute angle the one to the other and on which the two rows of needles, moving up and down at the same time in opposite directions, cooperate alternately with one or two thread-feed rings which have, however, no rigid connection with the spool carrier.

The invention will be hereinafter particularly described with reference to the accompanying drawings in which

Fig. 1 is a vertical part section through the machine,

Fig. 2 a section on line 2—2 of Fig. 1,

Fig. 3 a section on line 3—3 of Fig. 1.

Figs. 4 to 7 illustrate details which will be explained in the course of the description. The needle plates 1 and 2, situated obliquely in one plane, at an acute angle of 15 to 20° the one to the other and ring-shaped have milled grooves 3, one for each needle. The vertical, smooth arms of the needle plates stand the one opposite the other and are separated by a small interval 4 serving as passage for the goods.

The needles are latch needles (see Figs. 3 and 4), and they are alternately moved obliquely up and down by their feet which rest in a needle bar 5 or 6. During this movement they are prevented from jumping out by covering bars 3a, 3b (Fig. 2).

Under the point of intersection 7 (Fig. 1) of the needles between the two vertical arms, i. e. of the inner needle plate 2 and of the outer needle plate 1, the goods are drawn off in downward direction. For more securely holding the goods when the needles ascend fillets 8 are fixed on the arms

of the inner needle plate 2. The inner needle bar 6 is driven from the interior of the machine directly from the main drive, and the outer needle bar 5 is driven from the outside also by the main drive.

The two needle bars 5 and 6 are alternately in operation.

The two thread feeding rings 9 and 10 situated in one and the same plane circulate around the guide table 24 fixed on the uprights of the machine. The inner thread feeding ring 10 moves in clockwise direction, the outer ring 9 in anticlockwise direction. These thread feeding rings are not rigidly connected with the spool carriers 11, 11a, on which the warp threads to be treated are wound on spools or beams 25, 26. The spool carriers 11, 11a are disposed on rings 21, 28 which rotate around the axis of the machine in the same manner as the feeding rings 9, 10. The rings 21, 28 are provided on their adjacent edges with toothed rims 29, 30, which mesh with a gear wheel 31. This gear wheel 31 is not driven by any particular driving means but merely serves to balance irregularities in the rotation of the rings 21, 28 which are set in movement by the driven feeding rings 9, 10 through the tension of threads 14, 15.

Each of the thread feeding rings has as many holes as half the number of threads, one hundred or two hundred warp threads being wound on a separate spool or on warp beams 25, 26. These spools or warp beams move stepwise around the central axis of the frame as the thread feeding rings do.

On the thread feeding rings 9 and 10 needles 12 and 13 cast in lead are screwed and have each an eye. The warp threads 14 and 15 (Fig. 1) are threaded through the eyes of the needles and are perpendicularly above the point of intersection 7 of the needle plates 1 and 2 lying obliquely at an angle of 15 to 20° to the perpendicular. The thread feeding rings 9 and 10, when the corresponding needle bars 5 or 6 and the needle section are raised, shift in both lateral directions so far that the warp threads 14 and 15 (Fig. 1) come to lie on the breast of the needle, that is between latch and hook. These two threads, which are gripped by one needle, form their point of intersection directly on the needle breast, so that it is not necessary to impart to the needle any other up and down movement but a straight-lined one in order to ensure a secure gripping of the two intersecting threads by the hook of the latch needle.

After the descending movement of the needle 55

bar 5 or 6 the latches of all needles which are moved at the same time close and a fresh loop is knocked off in the customary manner when latch needles are employed. In the meantime the other one of the two needle bars has ascended. The warp threads 14 and 15 again come to lie upon the breast of the needles owing to the needle feeding rings 9 and 10, both threads being guided at either side. During the descending movement of the needle bar the latch closes with the thread and knocks off a fresh loop. Over every needle comes to lie the one thread of the thread feeding ring 10 rotating in clockwise direction and the other thread of the thread feeding ring 9 rotating in anticlockwise direction.

Referring to Figs. 4 to 7, Fig. 4 shows the loop formation on enlarged scale, whereas Figs. 6 and 7 show diagrammatically the operation of a number of needles seen from the outer side, i. e. from the left relative to Fig. 4; Fig. 7 shows the operation of the inner needles, i. e. seen from the right relative to Fig. 4. In Fig. 6 the needles 1, 3, 5, 7, 8, 11 are raised, whereas the needles 2, 4, 6, 8, 10, 12 are lowered. In Fig. 7 inversely the needles 3, 5, 7, 9, 11, 13 are raised, whereas the needles 2, 4, 6, 8, 10, 12 are lowered. From Figs. 6 and 7 the feedings for ribbed goods 1:1 can be seen, Figs. 4 and 5 show clearly how the loops are formed by the latch needles.

For easily threading the warp threads into the needle eyes the thread feeding rings 9 and 10 are lifted from their bearings by thin wire ropes so such a distance that the threading of the threads can be carried out unimpeded and rapidly. After the termination of this work the thread feeding rings are returned into their initial position.

The drive of the two thread feeding rings 9 and 10 is preferably effected by two toothed rims 20, 21 are arranged thereon with which spur wheels 22, 23 mesh, the spurs being driven from the main drive.

By provision of automatic reversing by means of counting chains and a lifting drum which will restrict the activity of the thread feeding rings 9 and 10, the advancing movement of the thread feeding rings may be interrupted as desired, so that both thread feeding rings are restricted to counter-movement forward and backward over one or several needles for loop formation. This forward and backward movement of the warp threads in opposite directions when using alternating coloured material, will produce a fabric with coloured longitudinal stripes.

Owing to the spaced arrangement of the thread feeding rings 9 and 10 with respect to the spool carriers 11 the weight of the material and of the spool carriers is not moved forward and backward as in the older constructions in which the guide rings are rigidly connected with the spool carriers, but in applicant's construction the spool carriers are at standstill and only the thread feeding rings with the thread warp threads move then alternately over one or several needles for the loop formation.

I claim:

1. In a circular warp knitting machine having two groups of warp threads, means for mov-

ing the threads in counter directions around the axis of the machine, a needle bed having needle grooves disposed at an acute angle to the vertical, two guide rings for the groups respectively adapted to move in counter directions about the axis of the machine, means for moving the guide rings, and means for moving the needles up and down in their grooves whereby the crossing point of each warp thread of one group with the corresponding thread of the other group will be disposed directly upon the shank of its related needle when in upper raised position.

2. In a circular warp knitting machine having two groups of warp threads, means for moving the threads in counter directions around the axis of the machine, two needle beds having needle grooves disposed at an acute angle to the vertical, two guide rings for the groups respectively adapted to move in counter directions about the axis of the machine, means for moving the guide rings, and means for moving the needles in counter action up and down in their grooves whereby the crossing point of each warp thread of one group with the corresponding thread of the other group will be disposed directly upon the shank of its related needle when in the upper raised position, the threads being gripped alternatively by the needles of the beds after the crossing points of the threads are formed on the respective needle shanks to form a ribbed tubular interlocked fabric.

3. In a circular warp knitting machine having two groups of warp thread bobbins and carriers, means for moving the carriers in counter directions around the axis of the machine, a needle bed having needle grooves disposed at an acute angle to the vertical, two guide rings for the groups respectively adapted to move in counter directions about the axis of the machine, means for moving the needles up and down in their grooves whereby the crossing point of each warp thread of one group with the corresponding thread of the other group will be disposed directly upon the shank of its related needle when in upper raised position, and means for driving the guide rings independently of the thread bobbins and carriers.

4. In a circular warp knitting machine having two groups of warp thread bobbins and carriers, means for moving the carriers in counter directions around the axis of the machine, two needle beds having needle grooves disposed at an acute angle to the vertical, two guide rings for the groups respectively adapted to move in counter directions about the axis of the machine, means for moving the needles in counter action up and down in their grooves whereby the crossing point of each warp thread of one group with the corresponding thread of the other group will be disposed directly upon the shank of its related needle when in upper raised position, the threads being gripped alternatively by the needles of the beds after the crossing points of the threads are formed on the respective needle shanks to form a ribbed tubular interlocked fabric; and means for driving the guide rings independently of the thread bobbins and carriers.

EUGEN HILLER.
